UNITED STATES PATENT OFFICE.

JAMES A. GRAY, OF SAN FRANCISCO, CALIFORNIA.

CAN-HEADING MACHINE.

SPECIFICATION forming part of Letters Patent No. 740,008, dated September 29, 1903.

Application filed August 8, 1901. Serial No. 71,382. (No model.)

To all whom it may concern:

Be it known that I, JAMES A. GRAY, a citizen of the United States, residing at San Francisco, in the county of San Francisco and State of California, have invented certain new and useful Improvements in Can-Heading Machines, of which the following is a specification.

My invention relates to machines for placing ends or heads upon tubular sheet-metal bodies; and my object is to simplify the construction of machines in this class, to reduce the number of operative parts, and to cheapen the cost of production. The accomplishment of these objects implies also a machine of great durability, an absence of small parts, reduced liability to get out of order, and infrequent necessity for repairs. In spite of the simplicity of its construction my machine is a high-speed automatic header, comparing very favorably in this respect with rotary headers of apparently greater capacity. Reasons for this will further hereinafter appear.

The essential features of a machine embodying my invention are coöperating jaws adapted to open and close, with which are associated means for supplying can-bodies and can-heads, mechanism for operating the jaw members, and means for placing a head or heads upon each body. The movement of the can-heads and can-bodies through the machine is of remarkable simplicity and directness, such bodies and heads being received into the separated jaws, inclosed by them, headed while so inclosed, and discharged from the jaws in the same line of direction at which they entered. The can members are not carried from place to place in the machine, but simply pass through it for a distance about equal to their own diameter, their passage being momentarily interrupted while the heads are applied. In high-speed rotary headers much time is lost in carrying a can from its point of entrance to its point of discharge, during much of which time the machine is inactive as regards that particular can. In the present machine the conservation of time as regards single cans has been carried to a high degree of perfection.

A machine in which my invention is embodied and which shows it in its simplest form is herein described, and shown in the ac-

companying drawings. It is a machine for heading salmon-cans with one head or bottom, but illustrates the principle of the invention completely. Further developments of the machine, so as, for instance, to apply two heads to one can-body, will be obvious to those skilled in this art after reading the following description and the drawings.

In the drawings, Figure 1 is a plan view of the whole machine with the feed-passages in section. Fig. 2 is a side elevation. Fig. 3 is a cross-section at $x x$ of Fig. 1. Fig. 4 is a detail view of friction-brake. Fig. 5 is a detail of a clutch which can be used to automatically throw the machine into gear. Figs. 6, 7, and 8 are illustrations of the movements of the movable pairs of jaws. Fig. 9 is an elevation of a movable can-head guard in position when upper jaws are open. Fig. 10 is a similar view of the same parts, but with upper jaws closed. Fig. 11 is a horizontal section of the same parts. Fig. 12 is a perspective view of one jaw member. Fig. 13 is a plan view of a modified form of machine differing from the view shown in Fig. 1 in that two can-heads are applied to a can-body by two oppositely-acting plungers. Fig. 14 is a plan view showing another modification of the invention in which two heads are applied to a can-body by a single plunger. Fig. 15 is a plan view which illustrates a double machine, each part of which acts substantially like the machine of Fig. 13 and in which by means of two plungers, a central abutment, and four can-head feeds two heads can be placed simultaneously upon two cans. Fig. 16 represents a slight modification of Fig. 15 and is really a duplication of the machine shown in Fig. 1, the construction being such that by means of two plungers and a central abutment with one can-head feed for each can two cans can be provided simultaneously with one head each. Fig. 17 is a perspective view of one of the jaws, such as shown in Fig. 12, but modified in form to suit conditions where two heads are applied at the same time to one can-body.

A represents any suitable supporting structure, and B B are side pieces of a frame secured therein and in which are formed guides 1 2, shown as of acute-angular shape, but which may be of right-angular or any other

cross-section, Fig. 3, for the upper members C C' and the lower members D D', the members C C' forming one pair, and the members D D' forming another pair, of coöperating jaws. The meeting faces of all the jaws are shaped so that when brought together, Fig. 8, they will conjointly surround and closely fit the can-bodies and can-heads, and such meeting surfaces have shoulders c, Fig. 12, forming an enlarged seat for the can-heads and forming a space around the edge of the can-body which enables the two to be forced together. If round cans are being headed, the face of each jaw will be hollowed out to an arc of ninety degrees, all forming together a sectional circular clamp or mold. The perspective view of one upper jaw, Fig. 12, gives a clear idea of its preferred shape and of the shapes of all four, which are substantially the same. Each has two rearwardly-projecting arms 3 and 4, both of which are beveled outwardly to fit the guides of the frame, and each arm 3 has an extension 5, projecting downwardly in upper jaws and upwardly in lower jaws.

A driving shaft E is journaled in bearings 7 on the supporting structure and has the miter-gears 8 and 9, which through similar gears drive at right angles the counter-shafts F and G, journaled at opposite ends of the machine. Each counter-shaft carries two disks H I, having cam-grooves 10 11. These cams project into the spaces between the arms 3 and 4, Fig. 1, and the grooves engage with rollers 12 13. Rollers 12 are on the upper jaws and engage grooves 10. Rollers 13 are on the lower jaws and engage grooves 11, and all the rollers are preferably journaled at the center line of the combined jaws—that is, an imaginary line between an arm 3 or 4 and the extension or projection 5.

Standards 16 17 on the machine-frame form a feed-passage for can-bodies, to which is connected any suitable feed device, such as the gravity-chute 18. Plates 19, secured to one of the standards, form a parallel vertical passage 20 for can-heads. In the assembly drawings Figs. 1, 2, 3 the jaws are in the position of Fig. 7, with lower jaws closed and upper jaws wide open. Hence both can-body and can-head can fall freely upon the closed lower jaws in position for heading. The next can body and head rest immediately upon their predecessors. No stops, spacing means, or feed-controlling devices are employed in the feed-passages. Referring to Fig. 2 and comparing cam-disk H, which controls the upper jaws, with cam-disk I, which controls the lower jaws, it will be seen that the upper jaws will next be pushed inwardly, while the lower jaws remain closed, since rollers 13 remain in the concentric part of grooves 11 for half a revolution. As the upper jaws come together they cut off the succeeding can and head and with the lower jaws closely surround and inclose the preceding can and head, Fig. 8. At this point

the head is applied by a plunger K, operated at right angles to the motion of the jaws, Figs. 1 and 2. The plunger has side guides 25 in the frame and carries a roller 26 in the path of a cam 27 on the main shaft E. Springs 28 bear on the plunger and throw it out, when the cam releases it. The can and head being now clamped and held by the jaws in proper relative position for heading, the plunger forces the head upon the body against the resistance of an abutment 29, shaped like the plunger, and then springs back, the cam having passed. At this time cam-disks I have made the half-revolution before referred to and act on the lower jaws, opening them fully, as shown in Fig. 6, and the headed can drops out, having moved from its entrance to its exit a distance of only about its own diameter, which is the combined thicknesses of the jaws. The cams which operate the lower jaws are shaped to give them a single continuous movement both in opening and closing; but the cams H, which operate the upper jaws, give them a special motion for two reasons. This is illustrated in Fig. 6, which is the position assumed following that of Fig. 8. When the can has been headed, both pairs of jaws commence to separate, and the lower jaws complete their opening movement and discharge the headed can, but the cams H, which operate the upper jaws, are so shaped as to retard their opening movement, causing them to separate slightly, Fig. 6, in order, first, to loosen the can just headed from any adhesion to the upper jaws, and, secondly, to let the succeeding can position itself ready to fall, as shown. The meeting edges of the jaws are preferably beveled or curved slightly, forming a seat 134, Fig. 6. The upper jaws are not opened widely enough to admit the succeeding can until the lower jaws have been closed, Fig. 7.

In order to keep the machine running easily and steadily and to prevent backlash, I use an adjustable friction or brake on one of the shafts, such as the counter-shaft F and which is shown in detail in Fig. 4. The end of the shaft has a tight collar 30, surrounded by a frictional band 31, of leather or other suitable material. Bolted to the machine-frame at 32 is a clamp 33, which exerts a pressure on the friction and which by a screw 34 can be regulated to adjust such pressure. This acts as a governor for the whole system of shafts and gearing and causes them to run regularly and smoothly, as also the reciprocating parts deriving motion from them.

Under some circumstances, as when running a small lot of cans through the machine, it is desirable to have the driving-shaft and the machine stop automatically when their work is finished without stopping the driving-pulley, and I have therefore devised an attachment whereby the successive can-bodies descending in the feed-passage throw the machine into gear. When the supply fails, the machine stops. This attachment is a conven-

ience, not a necessity; but I prefer to supply it with my machine. It is shown in Figs. 1, 2, and 3 and in detail in Fig. 5. The driving-shaft E has a fixed clutch-ring 35, in a recess of which is a pawl 36, held outwardly by a spring 37. The hub of the driving-pulley E' fits this sleeve and has notches 38 to receive the pawl when the machine is driving. The pawl can be forced into its recess and held there, with driving-shaft and clutch-ring stationary and pulley E' revolving idly, by an arm 39, secured at one end of rock-shaft 40. At the other end of shaft 40 is a link 41, to which is connected a lever 42, pivoted to the vertical standards and whose free arm 43 projects into the can-body feed-passage. Figs. 2 and 5 show clearly the operation of this clutch when driving. Should the supply of cans fail, the arm 39 will fall in over the pawl, depressing it into its recess, and hence stopping the clutch-ring 35, the driving-shaft, and all mechanism excepting the driving-pulley. While cans are being fed, the machine drives continuously, as their rapid succession allows no time for disengagement.

In Figs. 9, 10, and 11 I have shown details of a simple attachment which I prefer to use for keeping the can-head straight and in proper position until the jaws seize it along with the body. A loose plate 45, having a double wedge-shaped lower end 46, forms a movable extension of the inner wall between the can-body and can-head passages and is guided in the standards which bound said passages. Tongues 47 are secured to said wall and recessed into said plate. In the receptive position of the jaws, Fig. 9, the plate 45 drops by gravity, along with the can head and body, until two shoulders 48 rest upon the opened upper jaws, which form stops for them. The pointed lower end is now interposed between the can-head and can-body, and the head is held in its proper vertical position, Fig. 11. As the upper jaws close to position of Fig. 10, they force the plate 45 upwardly; but the latter acts as a support to the can-head until the jaws have closed, when the plate rests upon them. The tongues or strips 47 bridge the open space above the lowered plate 45, Fig. 9, and prevent succeeding can heads and bodies from striking the top of said plate by making a continuous smooth surface of the feed-passage.

This machine for putting on one head is capable of certain developments, which, it is believed, will be obvious to those skilled in the art without detailed description or illustration.

First. It is obvious that two heads can be applied to a can-body by gearing together the idle ends of the two counter-shafts by a fourth shaft E', making the abutment 29 a movable plunger 29^a and operating it from that shaft and forming a second can-head-feed passage 17^a opposite the one shown and forming the meeting jaw-faces with two shoulders c.

Second. In the machine shown, Fig. 1, the can-body is held in position while one head is applied by a stationary abutment 29. It is obvious, as shown in Fig. 14, that a can-head passage 17^b can be provided in front of that abutment, which will supply another can-head, into which the end of the body can be pushed by the single plunger shown, thus applying two heads with one plunger. In this case also the jaw-faces will have two shoulders c, Fig. 17.

In Fig. 15 is shown another modification in which the heading mechanism is duplicated, although the principle of each part remains the same, and the operating mechanism is all geared and connected together, so that it runs as one machine. In this case there is a central abutment 29^c, Fig. 15, two can-head-feed passages 17^c at opposite sides of the abutment, the usual can-head-feed passages shown in Fig. 1, and two plungers K like those in Fig. 1 driven by such a general arrangement of gears as has been described in connection with Fig. 13 and is shown there. Fig. 16 is, however, more properly a duplication of Fig. 1, because while in Fig. 15 two heads are put upon each can-body in Fig. 16 such duplicate mechanisms put only one head upon each can-body, as in Fig. 1. The central abutment is the same as in Fig. 15; but the can-head passages of Fig. 15 adjacent to said abutment are lacking. The arrangement of gearing in Fig. 16 is substantially the same as in Figs. 13 and 15. Such a double machine, Fig. 15 or Fig. 16, would be somewhat cheaper in construction than two complete single machines; but there are advantages in using two complete single machines, such as the ability to shut one down while running the other. I mention these modifications because they embody the essential principles of my invention and not necessarily because I consider them as improvements upon the construction shown.

Other modifications and equivalents within the spirit of my invention may be employed, and I therefore do not wish to limit myself to details of construction shown and described.

Having thus fully described my invention, what I claim as new, and desire to secure by Letters Patent, is—

1. In a can-heading machine, a pair of movable jaws, and a second pair of jaws having an independent movement, means for supplying can-bodies and can-heads to said jaws, means for effecting the said independent movements of the jaws, and heading means; whereby can bodies and heads pass through the opened jaws of one pair and are supported by the closed jaws of the other pair, are then surrounded and inclosed by all the jaws, are headed while so inclosed, and are then discharged through the opened second pair of jaws.

2. In a can-heading machine, a pair of movable upper jaws, and a pair of lower jaws having an independent movement, means for sup-

- plying can-bodies and can-heads to said jaws, means for effecting the said independent movements of the jaws, and heading means; whereby can bodies and heads fall through the opened upper jaws, and are supported by the closed lower jaws, are then surrounded and inclosed by all the jaws, are headed while so inclosed, and are then discharged, headed, through the opened lower jaws.
3. In a can-heading machine, two pairs of coöperating movable jaws, in combination with each other and with mechanism for operating said respective pairs of jaws independently to produce the following successive results; the closing of one pair of jaws while the other pair are opened to admit the members of a sheet-metal can; the closing of the other pair of jaws, so that the two pairs conjointly inclose said members; and the opening of the one pair of jaws to discharge the said members.
4. In a can-heading machine, two pairs of coöperating movable jaws, in combination with each other and with heading mechanism, and mechanism for operating said respective pairs of jaws independently and heading mechanism to produce the following successive results; the closing of one pair of jaws while the other pair are opened to admit the members of a sheet-metal can; the closing of the other pair of jaws so that the two pairs conjointly inclose said members, the uniting of said members while so inclosed and the opening of the one pair of jaws to discharge the said united members.
5. In a can-heading machine, two rectilinearly-movable upper jaws, two rectilinearly-movable lower jaws, each pair having meeting faces so shaped as to partly surround and conform to the shape of can-heads and can-bodies, heading means, and means for operating said pairs of jaws independently, so as to admit, surround and discharge said can bodies and heads.
6. In a can-heading machine, a pair of coöperating upper jaws, and a pair of coöperating lower jaws, all having meeting faces so shaped as to conjointly surround and conform to the shape of can bodies and heads, and means for operating said pairs of jaws independently so as to produce alternate open and closed positions of the pairs of jaws, and an intermediate position when all the jaws are closed.
7. In a can-heading machine coöperating upper jaws and coöperating lower jaws, adapted to be assembled to inclose can-bodies and can-heads, heading means, and cams connected to the individual jaw members; said cams being constructed so that after the assembling of the jaws and the heading of the can, the lower jaws are opened immediately to their full extent, while the upper jaws are temporarily retarded in their opening movement.
8. In a can-heading machine, a device for receiving and holding can bodies and heads and for discharging headed cans, comprising two inlet members, adapted to meet and recede from each other, and to inclose one half 70 the peripheries of can bodies and heads, and two outlet members adapted to meet and recede from each other, and to inclose the other half of said peripheries, in combination with means for placing said heads on said bodies, 75 and with means connected to said members and to said heading means, for producing the following sequence of operation: the opening of the inlet members so that can bodies and heads are received within the closed outlet members; the closing of the inlet members while the outlet members remain closed and so completely surrounding the bodies and heads; the placing of the heads upon the bodies while so surrounded; and the opening 85 of the outlet members to discharge the headed can.
9. In a can-heading machine, passages for can-heads and can-bodies in which said articles fall by gravity, in combination with movable jaws adapted to receive, clamp, and discharge said articles, and means for closing said jaws together across the discharge ends of all of said passages, whereby the jaws themselves act as cut-offs to succeeding articles, 95 while clamping preceding articles.
10. In a can-heading machine, a main frame, having adjacent passages for supplying can-bodies and can-heads, reciprocating jaws guided in said frame and moving in close 100 proximity to the discharge end of all of said passages; and means for reciprocating said jaws; whereby on the reception of can members within the opened jaws, succeeding can members can rest upon their predecessors, 105 and whereby on the closing of the jaws the succeeding members are cut off and rest upon the closed jaws.
11. In a can-heading machine, jaws for receiving, clamping and discharging can members, heading means, a system of driving-gearing, which includes a clutch mechanism, for operating said jaws and said heading means, a passage for feeding said can members and connections to said clutch mechanism adapted to be operated by said can members.
12. In a can-heading machine, jaws for receiving, clamping and discharging can members, heading means, a system of gearing for 110 operating said jaws and said heading means, a driving-pulley normally out of gear with said system of gearing, a passage for feeding said can members, a clutch mechanism, and connections to said clutch mechanism operated by said can members for gearing the pulley to the gear system.
13. In a can-heading machine, having open-bottomed unobstructed passages for can-heads and can-bodies, coöperating jaws conjointly 115 opening to receive, and closing to surround the said can members, and a vertically-movable guard in the said passages, adapted to accompany the can members into said jaws

when opened, and so to keep them separated and positioned while it is resting upon said open jaws, and to be removed from said jaws by the closing movement of the latter.

5 14. In a can-heading machine, parallel passages for can-bodies and can-heads, a wall separating said passages, a vertically-movable plate forming an extension of said wall, coöoperating jaws, conjointly opening to receive and closing to surround said can bodies and heads, and a double wedge-shaped extremity to said plate; whereby said extremity accompanies the can bodies and heads into and rests upon the open jaws; and is removed 15 therefrom by the bearing of the closing jaws against such double wedge.

15 15. In a can-heading machine, parallel feed-passages for can bodies and heads, a wall separating them, a vertically-movable plate 20 forming an extension of said wall, and tongues or bridges secured to the wall and recessed into the movable plate, for preserving a continuous surface between them when said plate has moved away from the wall.

25 16. In a can-heading machine, parallel feed-passages, separated by a wall, a movable plate forming an extension of said wall and

adapted to fall by gravity; coöoperating jaws opening and closing and adapted when open to receive the end of said plate, and stops or 30 shoulders on the plate adapted to rest on the open jaws.

17. In a can-heading machine, a member of a pair of jaws having a face shaped so as to partly surround can bodies and heads, 35 slides formed with said jaw, and an extension of one of said slides at an angle to it, and provided with a roller.

18. In a can-making machine, a member of a pair of jaws having a face shaped so as to 40 partially surround can bodies and heads, parallel arms extending from said face and forming slides, an extension of one of said arms, and a roller journaled to said extension with its axis in the plane of an imaginary line at 45 the junction of said arm and extension.

In testimony whereof I have affixed my signature, in presence of two witnesses, this 27th day of July, 1901.

JAMES A. GRAY.
